UNITED STATES PATENT OFFICE.

WILLIAM FERDINAND RILEY, OF SPOKANE, WASHINGTON.

PACKAGE-TIE.

1,351,344.

Specification of Letters Patent. Patented Aug. 31, 1920.

Application filed May 22, 1919. Serial No. 298,944.

To all whom it may concern:

Be it known that I, WILLIAM FERDINAND RILEY, residing at Spokane, in county of Spokane, State of Washington, a citizen of the United States, have invented certain new and useful Improvements in Package-Ties; and I do hereby declare the following to be a full, clear, and exact description of the invention, such as will enable others skilled in the art to which it pertains to make and use the same.

My invention relates to improvements in package ties and more particularly to a device for fastening, tying or binding trunks, boxes and other articles.

The object of the invention is to provide a tying or binding device capable of being readily adjusted to trunks, boxes etc. of various sizes.

A further object is to provide a tying device having means whereby after being placed in position or adjusted on the trunk, box or other article and tightened, will be capable of being tightened up still further and locked securely in place.

A further object is to provide a tying or binding device which is simple, inexpensive and durable in construction and easy and effective in use.

The invention consists in the several features and in the construction combination and arrangement of such features as more fully hereinafter described and claimed.

Referring to the drawings:—

Figure 1 is a top plan view of my invention shown as applied and locked on a trunk.

Fig. 2 is a top plan view of the tying or binding device with the locking lever shown in unlocked position.

Fig. 3 is an edge view of the tying or binding device.

Fig. 4 is a detail bottom plan view of the spring controlled pin.

In the drawings in which like reference characters denote like parts throughout the several views, 1 represents my improved tying or binding device which is provided with what are commonly known as sets of "lazy tongs" 2 and 2^a, one at each end thereof, each set of which comprises four arms 3, 4, 5 and 6 pivoted together by means of pivots 7, 8, 9 and 10 and being provided with lateral arms 11 and 12 pivoted respectively on the pivots 8 and 10 and longitudinal arms 13 pivoted on pivots 9. The arms 11, 12 and 13

are adapted to receive the end of the chains 13^a, straps or other devices used to bind or tie the trunk, box or other article.

The "lazy tong" 2^a is provided with a longitudinal link 14 which extends toward the "lazy tong" 2 and the "lazy tong" 2 is provided with a longitudinal link 15 pivoted on pivot 7.

A longitudinal locking lever 16 is provided, situated between the links 14 and 15, one end 17 of which is pivoted on a pivot 19 of the link 14 and also on a pivot 20 of the link 15.

The opposite end 21 of the locking lever 16 is turned or bent upward slightly in order that it may readily engage the upper surface of a pivoted latch 22 on arm 3, which is provided with a longitudinal slot 23 engaged by a spring controlled pin 24 projecting upward through the arm 3, of the "lazy tongs" 2^a, and locks the lever 16 securely in place.

In use the chains, straps, ropes or other tying means are adjusted in place around the trunk, box or other article with the ends thereof secured to the ends of the several arms 11, 12 and 13 and drawn as tightly around the trunk as is possible to do with the hands, the locking lever being in the position shown in Fig. 2, then the locking lever is thrown toward the front and its outer end placed on the surface of the latch, the latch moved to the left until the spring controlled pin 24 engages the slot 23 therein when the lever will be securely locked in place.

The movement of the locking lever to the left causes the set of adjustable arms to be moved toward each other all slack in the chains being eliminated, and causes the chains to be drawn tightly and immovably around the trunk and securely locked thereon by the locking lever by means of the link 15.

To remove the chains it is only necessary to press the pin 24 down until it clears and is disengaged from the slot 23 in the link, move the link downwardly until it releases the end of the locking lever and then throw the locking lever down to the right which will cause the chains to slack up and become loose on the trunk, when they may be easily removed.

I do not wish to be understood as limiting myself to the specific details of construction and arrangement as herein described and

illustrated, as it is manifest that variations and modifications may be made in the features of construction and arrangement in the adaptation of the device to the various 5 conditions of use without departing from the spirit and scope of my invention and improvements. I, therefore, reserve the right to all such variations and modifications as properly fall within the scope of my invention and the terms of the following claims:

What I claim is:—

1. In a tying or binding device, a plurality of sets of adjustable arms, the arms of each set pivotally connected together, links pivoted to said arms, a lever situated intermediate said links and pivotally connected to each of said links and adapted to move the said sets of adjustable arms toward and from each other and means for locking said lever.
2. In a tying or binding device, a plurality of sets of lazy tongs each having a plurality of lateral arms pivoted thereto, tying or binding means connected to said arms, and a lever connecting said lazy tongs and adapted to move them toward and from each other.
3. In a tying or binding device, a plurality of sets of lazy tongs each having a plurality of arms pivoted thereto, tying or binding means connected to said arms, a lever connecting said lazy tongs and adapted to move them toward and from each other and

means on one of the lazy tongs for locking said lever.

4. In a tying or binding device, a plurality 35 of sets of lazy tongs each having means for receiving the tying means, longitudinal links pivoted to said lazy tongs, a lever pivotally connected to said longitudinal links, a latch pivoted to one of the lazy tongs adapted to 40 receive the end of the lever and a pin on the said lazy tongs engaging said latch and thereby locking the lever thereon.

5. In a tying or binding device, a plurality 45 of sets of lazy tongs, a lever operatively connecting said lazy tongs and adapted to move them toward and from each other, a pin, and a latch having a slot and mounted on one of the sets of lazy tongs, said pin adapted to engage the slot of the latch and 50 lock said lever when placed on said latch.

6. In a tying or binding device, a plurality 55 of sets of lazy tongs, a lever operatively connecting said lazy tongs and adapted to move them toward and from each other, a spring controlled pin, and a latch having a slot and mounted on one of the sets of lazy tongs, said pin adapted to engage the slot of the latch and lock said lever when placed on said latch.

In testimony whereof I have affixed my signature.

WILLIAM FERDINAND RILEY.
